(57) **CLAIM**

The ornamental design for a holder for tools and pipes, as shown and described.

DESCRIPTION

FIG. 1 is a bottom, left, front perspective view of the holder for tools and pipes according to our design;

FIG. 2 is a top, plan view thereof;

FIG. 3 is a right side view thereof;

FIG. 4 is a left side view thereof;

FIG. 5 is front view thereof;

FIG. 6 is a rear view thereof, with the broken lines being portions of the holder for tools and pipes that form no part of the claimed design; and,

FIG. 7 is a bottom, plan view thereof.

The broken line showings are included for the purpose of illustrating environment and form no part of the claimed design.
